The ornamental design for a multi-unit, individually removable, food dispensing package, as shown and described.

[21] Appl. No.: **589,332**

DESCRIPTION

[22] Filed: **June 23, 1975**

FIG. 1 is a front perspective view of a multi-unit, individually removable, food dispensing package embodying our new design.

[51] **Int. Cl. .... D9—03**

FIG. 2 is a front scale elevational view on a reduced scale from that of FIG. 1;

[52] **U.S. Cl. D9/191**

FIG. 3 is a rear elevational view thereof;

[58] **Field of Search .... 206/461—473,**

FIG. 4 is a side elevational view on a scale larger than that of FIGS. 2 and 3 but smaller than that of FIG. 1;

206/497—498, 801, 45.31—45.34; D9/182,

FIG. 5 is a top plan view thereof; and

184, 191, 192

FIG. 6 is a bottom plan view thereof.
